CLAIM

We claim, the ornamental design for a lighting fixture, as shown and described.

DESCRIPTION

FIG. 1 is a front left perspective view from below of a lighting fixture according to the new design;

FIG. 2 is a front right perspective view from above thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top view thereof;

FIG. 8 is a bottom view thereof;

FIG. 9 is a front left perspective view from below thereof, but shown illuminated;

FIG. 10 is a front right perspective view from above thereof;

FIG. 11 is a front elevational view thereof;

FIG. 12 is a left side elevational view thereof;

FIG. 13 is a right side elevational view thereof;

FIG. 14 is a rear elevational view thereof;

FIG. 15 is a top view thereof; and,

FIG. 16 is a bottom view thereof.

The break lines in the drawings indicate a symbolic break and the appearance of any portion of the lighting fixture between the break lines forms no part of the claimed design. The breakaway lines in the figures indicate a symbolic break in the length of the design indicating no specific length. The stippling shown in FIGS. 9-11 and 14-16 is solely for the purpose of illustrating the appearance of illumination and does not represent texture or surface ornamentation.
